TIP FOR CUTTING TORCHES

Arthur J. Fausek and Irving F. Fausek,
St. Louis, Mo.

Application July 22, 1929, Serial No. 380,231

6 Claims. (Cl. 158—27.4)

This invention relates generally to metal cutting apparatus and more specifically to that type of metal cutting apparatus with which burning gas is used for performing the cutting operations, 5 the predominant object of the invention being to produce an improved tip for a metal cutting torch of the gas burning type, which is so constructed that hydrocarbon gases may be efficiently employed as fuel gases in the use of such cutting torches.

It has recently become quite desirable to employ hydrocarbon gases, such for instance as propane ($C_3 H_8$), as fuel gas in the use of gas burning cutting torches, instead of acetylene and 15 other gases formerly employed, but because of certain characteristics of these hydrocarbon gases it has been found that efficient use may not be made thereof in the operation of cutting torches when torch tips are employed, of the type used 20 with cutting torches burning acetylene and other gases heretofore used as the fuel gases.

An important characteristic of the hydrocarbon gases referred to when compared with acetylene, for instance, resides in the fact that the 25 flame temperature of a combustible mixture which includes hydrocarbon gases as an element thereof is substantially lower than the flame temperature of a combustible mixture which includes acetylene. Because of this fact it is necessary to concentrate the heat of the hydrocarbon flame at a given point so that the required 30 heat may be present to enable the hydrocarbon flame to efficiently perform the cutting operation. Also because of the lower flame temperature of 35 a combustible mixture which includes hydrocarbon gases, the tip orifices through which the combustible mixture passes must be larger than tip orifices through which acetylene would pass. This arrangement of increasing the diameters of 40 the orifices results in the passage through said orifices of a greater volume of gas which tends to offset the lower flame temperature of the hydrocarbon gas flame.

In view of the foregoing we have devised the 45 torch tip disclosed in the present application which briefly stated comprises forming the passageways for the gas providing the preheating flames of the torch at such an angle that the heat 50 of the preheating flames is concentrated at a given point, and increasing the diameters of said passageways so that a greater volume of gas will pass therethrough than heretofore in the case of tips employed when acetylene was used as the 55 fuel gas.

Figure 1 is an enlarged section through our improved tip.

Figure 2 is a section of the body portion of the improved tip.

Figure 3 is a section of the element which provides the discharge end of the tip. 60

Figure 4 is a cross-section on line 4—4 of Figure 1.

Figure 5 is a fragmentary view partly in side elevation and partly in section showing our tip 65 applied to a cutting torch.

Figure 6 shows a modified form of our tip.

In the drawing, wherein is shown for the purpose of illustration, merely, one embodiment of the invention, A designates our improved cutting tip which comprises a body portion B and a separable element C arranged at the outer end of the body portion B and providing the discharge end of the tip. The body portion B is provided with a screwthreaded stem 1 at its upper end at the lower 75 end of which a flange 2 is arranged which provides a shoulder 3. Extended downwardly from the lower end of the body portion B is a second stem 4, the last mentioned stem being of less diameter than the stem 1 and having a smooth outer 80 face. At a point immediately adjacent to the inner end of the stem 4 the body portion B of the tip A is provided with screwthreads 5 which are intended for a purpose to be hereinafter set forth. Formed through the body portion B and stem 4 85 is a central gas passageway 6 for the cutting jet of the torch, said gas passageway preferably being of reduced diameter for a portion of its length at a point adjacent to the lower end of the stem 4 as designated by the reference character 7. Extended diagonally through the body portion B from the shoulder 3 to the bottom face 8 thereof is a plurality of passageways 9 for the gas which provides the preheating flame of the torch with which the tip A is associated. The passageways 9 are preferably formed in a circular row about the central passageway 6. 90

The element C of our improved tip is preferably tubular in cross-section and is provided at its upper end with a screwthreaded opening 10 100 and said element is attached to the body portion B by having the portion of said body portion which is provided with the screwthreads 5 screwed into said screwthreaded opening 10, said parts being screwed together until the shoulder 11 of the body portion contacts with the top face of the element C as shown in Figure 1, at which time the bottom face 8 of the body portion will be substantially aligned with the bottom of the screwthreaded opening 10. 105

At the lower end of the element C same is provided with a wall 12 which is of substantial thickness and said wall 12 is provided with a vertically extended centrally disposed opening 13 through which the stem 4 of the body portion B extends. As shown clearly in Figure 1 the bottom face of the stem 4 and the bottom face of the element C are substantially flush with each other. By referring to Figure 1 of the drawing it will be noted 10 when the element C is attached to the body portion B that a chamber 14 is provided within said element C, said chamber being defined by the inner face of the side wall of the element C and by the face 8 of the body portion at the top of said chamber and by the top face of the wall 12 of the element C at the bottom of the chamber.

15 designates gas passageways formed in the bottom wall 12 of the element C, said gas passageways providing conduits for gas which provide 20 the preheating flames of the torch and preferably being formed in a circular row around the central passageway 6. The passageways 15 are formed at a substantial angle with respect to the axis of the tip A, this angle being within a range 25 extended from 13° to 20° with respect to said axis, and said gas passageways 15 being arranged at an angle with respect to the gas passageways 9. At the lower end of each of the passageways 15 the wall 12 of the element C is provided with a depression 30 which serves to protect the inner end of the preheating flame issuing from said passageway from cold air currents which may tend to distort said flame. By employing the separable element C we are enabled to arrange the lower 35 portions of the preheating holes at a substantial angle without unduly increasing the diameter of the tip.

In the use of a cutting torch provided with our improved tip, gas providing the preheating flames 40 passes from the torch into and through the passageways 9 in the body portion B of the tip A, said gas being discharged from the passageways 9 into the chamber 14. This preheating gas then passes from the chamber 14 through the passageways 15 and is burned on issuing from the discharge end of said passageways to produce the 45 preheating flames.

The inclination of the preheating gas passageways 15 is of the essence of the present invention 50 inasmuch as without properly inclined preheating passageways hydrocarbon gases may not be efficiently used for metal cutting purposes. These gas passageways 15 as shown in the drawing are formed on an angle which is precisely 18° with respect to the axis of the tip A, and for a tip of the size of the one illustrated such an arrangement of the passageways 15 results in the maximum efficiency. However, very good results are obtained 55 when the angle of the passageways is slightly less or more than 18° and after long experimentation it has been determined that for tips of various sizes the angle of the preheating gas passageways may be from 13° to 20° with respect to the axis of the tip.

60 The angle of the gas passageways 15 causes the preheating flames issuing from said passageways to converge to a predetermined point, which point is designated in Figure 5 by the reference character P, and because of such convergence of said flames the heat thereof is concentrated at the point P. The distance from the end of the tip to the point P defines the flame length of the preheating flames and because the passageways 15 are arranged at an angle with respect to the 65 axis of tip within the range referred to above

there will be no breaking up or distortion of the flame at the point P, hence, the maximum heat will be concentrated at said point to efficiently perform the cutting operation. As will be seen by referring to Figure 5 the preheating flames 80 F merge with the cutting jet J at the point P and because of the angle at which the gas passageways 15 are formed there is no breaking up or spreading of jet J and flames F hence the torch will function with the maximum efficiency. 85

Due to the fact that the lower flame temperature when hydrocarbon gases are burned necessitates a greater volume of gas being passed through the gas passageways of the tip these passageways in our improved tip are of greater diameter than standard practice in connection with the manufacture of tips used for burning acetylene and other gases employed heretofore. 90

In Figure 6 we illustrate a modified form of the invention in accordance with which a single 95 annular depression 16' is employed, in which the discharge ends of the gas passageways 15 are disposed.

We claim:

1. A tip for cutting torches comprising a body 100 portion provided with a central gas passageway extended axially therethrough, gas conduits formed longitudinally through said body portion through which gases for providing preheating flames flow, a separable element attached to 105 said body portion at the discharge end of the tip, and gas conduits formed in said separable element, the last mentioned gas conduits being complementary to the first mentioned gas conduits and being arranged at an angle with respect to the 110 central gas passageway and at an angle with respect to the first mentioned gas conduits.

2. A tip for cutting torches comprising a body portion provided with a central gas passageway 115 extended axially therethrough, gas conduits formed longitudinally through said body portion through which gases for providing preheating flames flow, a separable element attached to said body portion at the discharge end of the tip and gas conduits formed in said separable element, 120 the last mentioned gas conduits being complementary to the first mentioned gas conduits and being arranged at an angle of from thirteen to twenty degrees with respect to the central gas passageway and at an angle with respect to the 125 first mentioned gas conduits.

3. A tip for cutting torches comprising a body portion provided with a central gas passageway extended axially therethrough, gas conduits formed longitudinally through said body portion 130 through which gases for providing preheating flames flow, a separable element attached to said body portion at the discharge end of the tip, gas conduits formed in said separable element, the last mentioned gas conduits being complementary to the first mentioned gas conduits and being arranged at an angle with respect to the 135 central gas passageway and at an angle with respect to the first mentioned gas conduits, and a chamber within the tip interposed between the first mentioned gas conduits and the second mentioned gas conduits.

4. A tip for cutting torches comprising a body portion provided with a central gas passageway extended axially therethrough, gas conduits formed 145 longitudinally through said body portion through which gases for providing preheating flames flow, a separable element attached to said body portion at the discharge end of the tip, gas conduits formed in said separable element, the last 150

mentioned gas conduits being complementary to the first mentioned gas conduits and being arranged at an angle of from thirteen to twenty degrees with respect to the central gas passageway and at an angle with respect to the first mentioned gas conduits.

5. A tip for cutting torches and the like comprising an element provided with a central gas passageway extended axially therethrough, gas conduits formed longitudinally through said element through which gases for providing preheating flames flow, a separable element attached to said body portion at the discharge end of the tip, a stem formed integral with said body portion and extended through said separable element, and gas conduits formed in said separable element, the last mentioned gas conduits being comple-

mentary to the first mentioned gas conduits and being arranged at an angle with respect to the central gas passageway and at an angle with respect to the first mentioned gas conduits.

6. A tip for cutting torches and the like comprising an element provided with a central gas passageway extended axially through the tip, gas conduits formed longitudinally through said element through which gases for providing preheating flames flow, said gas conduits at the discharge end portion of the tip being formed at an angle of from thirteen to twenty degrees with respect to the central gas passageway, and said discharge end portion of the tip being in the form of a one-piece integral structure through which portions of said gas conduits extend.

10. A tip for cutting torches comprising a body portion provided with a central gas passageway extended axially therethrough, gas conduits formed longitudinally through said body portion through which gases for providing preheating flames flow, a separable element attached to said body portion at the discharge end of the tip, a stem formed integral with said body portion and extended through said separable element, and gas conduits formed in said separable element, the last mentioned gas conduits being comple-
